UNITED STATES PATENT OFFICE.

JAMES BURTON PRATT, OF FORT JONES, CALIFORNIA.

QUARTZ MILL.

Application filed July 23, 1925. Serial No. 45,850.

The present invention relates to a crushing mill for quartz used in the process of concentration, and has for its object to provide an improved discharge end, which will insure the delivery of crushed ore at a uniform fineness.

In the drawing:

Figure 1 is a side elevation of the mill embodying the features of my invention.

10 Figure 2 is a longitudinal section therethrough.

Figure 3 is an end elevation thereof, and

Figure 4 is another end elevation thereof, showing portions in section.

15 Referring to the drawing in detail, it will be seen that 1 designates a drum having an end 2 therein, and also having my improved end indicated generally by the letter A, in the other end thereof. The end 2 has the central opening 3, which registers with the bore of the hollow shaft 4, journaled as at 5, and fixed to the end 2. This hollow shaft forms an entrance for the ore to the drum 1. In the drum 1 there is adapted to be disposed the well-known crushing bars (not shown) so that the ore will be crushed upon rotation of the drum.

20 Particular attention is now called to my improved end A. The numeral 6 designates a disc having a centrally disposed hub 7, which is reduced at its end, as at 8, to form an annular shoulder 9. A plurality of partition plates are arranged to extend rectangularly on the outer surface of the disc

25 6 and are indicated by the numeral 9. These plates radiate from the hub 7 and the outer edges thereof taper inwardly. These plates 9 form compartments indicated by the letters B. In each compartment B the disc 6 is provided with a plurality of rows of openings 10, of a relatively small gage and an opening 11, of a large gage, adjacent the hub, it being noted that the rows of openings 10 start adjacent the edge of the disc and are concentrically arranged, the inner row being disposed an appreciable distance from the opening 11. A screen band 12 of foraminous material of a suitable gage is disposed about the outer ends of the plates 9.

30 The disk 6 is held in place by bolts 13, passing through the drum 1 and the flanges on the disk 6. The band 12 is held in place by bolts 13, Figure 1. A plurality of closure plates 14 extend between the hub 7, at the shoulder 9 and the band 12, there being one plate over each compartment B. A

shaft 15 extends co-axially from the hub 7, in journals 16 and may be driven in any suitable manner. As the ore is fed through the hollow shaft 4 into the rotating drum 1, 60 it is crushed by the usual crushing bars (not shown) in the well known manner. The crushed ore will pass through the openings 10 into the compartments B. The ore which is fine enough will pass through the screen 65 band from the bottom compartment, whereas the ore which is not fine enough will be moved around the axis of the drum until the compartment is above the axis and the ore will flow back through the opening 11 70 into the drum to be recrushed. A supply of closure plates 18 are used, in association with the openings 10. These plates will be furnished in different sizes, varying substantially as is indicated to advantage in Figure 4, so that any number of the rows of openings 10 may be closed. These plates 75 18 hold the sand back in the mill or drum, and allow it to be thoroughly amalgamated inside the drum. In practice, approximately 90% of the values are kept inside the drum, very little gets out of the discharge end, and what does, is caught on the plates. If the operator desires to retain 80 more of the sand in the drum, he puts on wider plates. This decreases the capacity 85 to some extent, but holds back the sand. If the operator is running rich ore, the plates can be raised quite high, and adjusted to suit the conditions. 90

It is thought that the construction, operation, and advantages of this invention will be clearly understood and appreciated by those skilled in this art, without a more detailed description. It is desired, however, that the present embodiment of the invention has been disclosed merely by way of example, and attains all of the features of advantage enumerated as desirable in the statement of the invention and the above 95 description. It is apparent that numerous changes in the details of construction, in the sizes, and in the combination and arrangement of parts may be resorted to without departing from the spirit or scope of 100 the invention as hereinafter claimed or sacrificing any of its advantages. 105

Having thus described my invention, what I claim as new is:

110 1. A mill of the class described including a drum, a discharge end in the drum comprising a disc having a centrally located

hub, partitions radiating from the hub to form compartments, said disc provided with a plurality of rows of openings in each compartment, and a single opening in each compartment adjacent the hub, the single opening being relatively large in comparison with the other openings, closure plates over the outer sides of the partitions, a foraminous band disposed about the outer ends of the partitions.

2. A mill of the class described including a drum, a discharge end in the drum comprising a disc having a centrally located hub, partitions radiating from the hub to form compartments, said disc provided with a plurality of rows of openings in each compartment, and a single opening in each compartment adjacent the hub, and inclined inwardly toward the center of the drum, the single opening being relatively large in comparison with the other openings, closure plates over the outer sides of the partitions, a foraminous band disposed about the outer ends of the partitions, and closure plates adapted to be placed over a desired number of rows of the smaller openings in the disc.

3. An end structure for a mill drum including a disc having a hub portion reduced to form an annular shoulder intermediate its ends, partitions extending radially from the hub and rectangularly from the outer surface of the disc, closure plates on the outer sides of the partitions being engaged against the annular shoulder, a foraminous

band disposed about the outer end of the partitions, said partitions forming compartments, said discs provided with a plurality of relatively small openings in the outer portion of the compartment, and a single relatively large opening in the inner portion of the compartment.

4. An end structure for a mill drum including a disc having a hub portion reduced to form an annular shoulder intermediate its ends, partitions extending radially from the hub and rectangular from the outer surface of the disc, closure plates on the outer sides of the partitions being engaged against the annular shoulder, a foraminous band disposed about the outer end of the partitions, said partitions forming compartments, said discs provided with a plurality of relatively small openings in the outer portion of the compartment, and a single relatively large opening in the inner portion of the compartment, and adjustable closure plates for the relatively small openings.

5. A drum having a discharge end, said end made up of a disk having a series of openings about and adjacent to its center, compartments disposed at the outer side of the disk with each compartment in communication with one of said openings, and an annulus surrounding the said compartment and having interstices.

In testimony whereof I affix my signature.

JAMES BURTON PRATT.
